(57) **CLAIM**

The ornamental design for an automotive vehicle front seat, as shown and described.

DESCRIPTION

FIG. 1 is a front-perspective view of an automotive vehicle front seat, of the new design;

FIG. 2 is a rear-perspective view thereof;

FIG. 3 is a front view thereof;

FIG. 4 is a side view thereof;

FIG. 5 is a top view thereof;

FIG. 6 is a rear view thereof;

FIG. 7 is a side view thereof, opposite that of FIG. 4; and, FIG. 8 is a bottom view thereof.

The stippled portions are a darker color than the other portions. The broken lines are for environmental illustrative purposes only and form no part of the claimed design.

1 Claim, 8 Drawing Sheets
